UNITED STATES PATENT OFFICE

KARN TAKEMI, OF NEW YORK, N. Y.

DISPENSING-CLOSURE.

1,208,695.

Specification of Letters Patent. Patented Dec. 12, 1916.

Application filed June 27, 1916. Serial No. 106,164.

To all whom it may concern:

Be it known that I, KARN TAKEMI, a subject of the Emperor of Japan, and resident of New York, in the county of New York and State of New York, have invented certain new and useful Improvements in Dispensing-Closures, of which the following is a specification.

The present invention relates to dispensing devices and has particular reference to new and useful improvements in liquid and the like measuring devices of the predetermined bulk type.

The primary object of my invention is to provide a removable dispensing closure for containers having improved valve means associated therewith for dispensing the contents of the container in predetermined quantities.

Another object of my invention is to provide a device of the character described which may be quickly and easily attached to any container, without altering the structure of the container, the device being light in construction, strong and durable and cheap to manufacture.

A further object of my invention is to provide a new and improved valve for association with the measuring device for measuring and controlling the dispensing of the contents of a container.

Other objects and advantages to be derived from the use of my improved dispensing closure will appear from the following detail description and the claims, taken with an inspection of the accompanying drawing, in which:

Figure 1 is a side elevational view of a container showing my improved measuring closure applied thereto; Fig. 2 is an enlarged detached perspective view of the movable measuring element or valve; and Fig. 3 is a similar view of the body of the device, the parts being separated.

Referring more particularly to the drawing, wherein similar characters of reference designate like and corresponding parts throughout the various views, 1 designates a container, in the present instance, a bottle having the usual neck 2 extending therefrom. In the form of my invention shown I have illustrated the same applied to a bottle, but it will be readily understood that I do not limit the application of the device to this use.

The measuring device of my invention in-

cludes a base or supporting portion 3 reduced as at 4 for entrance into the neck 2 of the bottle 1, said base 3 having an annular laterally extending flange 5 formed thereon adjacent the reduced portion, a rubber or cork washer 6 being receivable about the reduced portion beneath the flange.

The body of the dispensing device is designated 7, in its entirety and is composed of two detachable sections 8 and 9, said sections having conical free end portions 10 and 11, respectively, said conical portions being formed with inlet and outlet substantially triangular openings 12 and 13, respectively. The portion 8 is reduced in diameter as at 14 and is adapted for snug reception within the base 3. The section 9 is provided with a slot 15 extending longitudinally of said section from the free marginal edge thereof, said slot being formed with a semi-circumferentially extending portion 16. The free open end of the section 8 is adapted to receive the section 9, a longitudinally extending elongated depression 17 being formed in the section 8 for engagement in the slot 15, whereby to prevent relative turning of the sections when joined. The sections when joined, preferably tightly engage each other in order to obviate the necessity of soldering to prevent separation of the sections.

The valve member preferably includes a tubular body 18 cut away as at 19 and 20 to form valve wings 21 and 22, the free ends 90 of the valve wings 21 and 22 having semi-conical portions 23 and 24, arranged relatively approximately at right angles for closing communication through the inlet and outlet openings 12 and 13, respectively. It 95 is to be understood, of course, that when the sections 8 and 9 are joined the valve member 18 is arranged for concentric rotative movement in said joined sections, the valve wings of said valve member 18 being adapted to engage to close the openings 12 and 13 simultaneously or alternately in a manner which will hereinafter appear. A manipulating handle 25 extends radially from the valve member 18 through the slots 15 and 16 for an obvious purpose.

It will be seen that in use when a predetermined quantity of liquid is desired the measuring closure of my invention is inserted in a container as shown in Fig. 1. 110 When the handle 25 is in the position shown in Fig. 1 the inlet opening 12 is closed and

the outlet opening 13 is opened. By placing the handle at the neutral or central position in the slot 16 both of the openings 12 and 13 are closed. The measuring operation is performed by inverting the bottle or container and opening the inlet valve 12. This will permit some of the contents of the bottle to enter the body of the measuring device. Moving the handle 25 to close the inlet opening opens the outlet opening permitting the contents of the dispensing device to flow out through said opening. The dispensing device may be made in different sizes for different quantities or measurements as desired. It will be seen that by increasing the diameter of the washer 6 various sizes of outlet openings of containers may be accommodated. All of the parts are intended to snugly yet freely engage whereby to prevent leakage. Therefore, the intermediate portion of the valve member 18 is made relatively wide in order to prevent possible leakage through the opening or slot 16.

From the above description taken in connection with the accompanying drawing, it is thought that a clear and comprehensive understanding of the construction, operation and advantages of my invention may be had, and while I have shown and described the device as embodying a specific structure, I desire that it be understood that such changes may be made in said structure as do not depart from the spirit and scope of the invention as claimed.

Copies of this patent may be obtained for five cents each, by addressing the "Commissioner of Patents, Washington, D. C."

Having thus fully described my invention, what I claim as new and desire to secure by Letters Patent, is:—

1. In a measuring closure, a base, means for engaging said base with a container, a body formed in sections and receivable on said base, said sections having openings therein, and a valve element rotatively arranged in the body and having angularly related wing portions for engagement with said openings, at times.

2. A dispensing closure, including a body formed in two detachable sections, one of said sections being provided with an elongated depression, the other section being provided with an elongated slot to accommodate the said depression and to prevent relative movement of the sections, the ends of said sections having oppositely arranged triangular openings, the last mentioned section having a slot therein extending semi-circumferentially of the said section, a tubular body member, the ends of the said tubular body member having semi-conical portions arranged approximately at right angles, the tubular member having portions adjacent the ends cut away to form valve wings, a manipulating handle extending radially from the tubular member and intermediate its ends, upon operation of the said handle the tubular member is rotated and thereby operating the valves.

In testimony whereof, I affix my signature hereto.

KARN TAKEMI.
